UNITED STATES PATENT OFFICE.

FRANK W. BLAKESLEE, OF ASHTABULA, OHIO, ASSIGNOR OF ONE-HALF
TO GEORGE O. BJORNEBY, OF WILLIAMSBURG, VIRGINIA.

BUILDING-BLOCK.

SPECIFICATION forming part of Letters Patent No. 760,774, dated May 24, 1904.

Application filed December 19, 1903. Serial No. 185,891. (No model.)

To all whom it may concern:

Be it known that I, FRANK W. BLAKESLEE, a citizen of the United States, residing at Ashtabula, in the county of Ashtabula and State 5 of Ohio, have invented a certain new and useful Improvement in Building-Blocks, of which the following is a specification.

This invention relates to the art of manufacturing building-blocks, and has for its object 10 the exclusion of heat, cold, dampness, frost, and the like.

In carrying out this invention it is proposed to make use of dead-air spaces for the exclusion of frost and the like, as will be herein- 15 after more fully described, shown in the accompanying drawings, and particularly pointed out in the appended claims, it being understood that changes in the form, proportion, size, and minor details may be made within 20 the scope of the claims without departing from the spirit or sacrificing any of the advantages of the present invention.

In the drawings, Figure 1 is a detail perspective view of a portion of a wall constructed 25 of the present form of blocks. Fig. 2 is a perspective view of a building-block embodying the features of the present invention. Fig. 3 is a similar view of an end or corner block. Fig. 4 is a cross-sectional view on the 30 line 4 4 of Fig. 2. Fig. 5 is a similar view on the line 5 5 of Fig. 3. Fig. 6 is a longitudinal sectional view on the line 6 6 of Fig. 4. Fig. 7 is a similar view on the line 7 7 of Fig. 5. Fig. 8 is a cross-sectional view of a modified form of block. Fig. 9 is a detail vertical 35 sectional view taken longitudinally through a portion of a wall constructed of the present form of blocks. Fig. 10 is a cross-sectional view thereof.

40 Like characters of reference designate corresponding parts in each and every figure of the drawings.

As has been hereinbefore stated, the object 45 of the present invention is accomplished by means of dead-air spaces which are arranged so that one or more of the spaces will intersect

any horizontal plane passing through the block. The preferred arrangement of air-spaces has been shown in Figs. 1, 3, and 5 of the drawings, wherein the numeral 1 indicates the block, which in the present instance has been illustrated as rectangular in form; but it will of course be understood that the shape of the block is immaterial and may be varied at will according to requirement. In 55 the block are formed at least two longitudinal parallel grooves or openings 2 and 3, of which the opening 2 intersects the bottom of the block and terminates short of the top thereof, while the groove 3 intersects the top and terminates short of the bottom, both grooves or openings extending throughout the entire length of the block and intersecting the opposite ends thereof. It will also be noted that the grooves or openings extend at least be- 60 yond the middle of the block, whereby they overlap, and therefore there is no solid portion entirely through the block—that is to say, a horizontal plane passed through the block at any point will intersect one or more air-spaces. 70 While only two grooves or openings have been shown in Figs. 1, 3, and 5, it will of course be understood that a greater number of openings may be employed—as, for instance, three grooves, as shown in Fig. 8, 75 wherein the grooves or openings 2 and 3 which intersect the top and bottom, respectively, of the block are comparatively shallow and a central longitudinal opening 4 has been formed through the middle of the block, 80 terminating short of the top and bottom thereof, but having its top and bottom portions overlapping the inner portions of the grooves 2 and 3, whereby there is no continuous solid portion through the block from front to rear. 85

In building a wall with the present form of blocks they are placed one upon the other in the common or ordinary manner; but, as indicated in Figs. 9 and 10, it is preferred to arrange the blocks so that the upper groove of 90 the lower block registers with the open end of the lower groove or opening of the upper

block, so as to produce a comparatively large dead-air space extending the entire length of the wall and of a height equal to the combined depths of the two grooves or openings. By 5 this arrangement inner and outer vertical series of horizontal dead-air spaces are produced, with the air-spaces of each series disposed opposite the respective intervals between the adjacent air-spaces of the other series and overlapping said adjacent air-spaces. 10 In a wall of this character there are no solid portions continuous from the outer to the inner sides of the wall, and therefore frost and the like cannot pass through the wall, as 15 the dead-air spaces effectually exclude the same. To be effectual for excluding frost and the like, the spaces must be dead—that is to say, entirely closed to the external air—so as to prevent circulation therethrough, and 20 therefore it will be understood that each air-space is closed at its opposite ends. For conveniently closing each air-space I have provided a corner or end block, as indicated in Fig. 3, wherein the openings or spaces intersect one end only of the block and terminate 25 short of the opposite end thereof, whereby the grooves or spaces are open at one end and closed at the other.

By reason of the effective exclusion of frost 30 and the like plastering 5 may be applied directly to the inner side of a wall constructed of the present form of building-blocks, thereby obviating the usual studding and laths.

While the present invention has been primarily 35 intended for artificial blocks by molding the grooves or openings therein, it will of course be understood that the grooves or openings may be cut in the block after it has been molded, and natural building-blocks may 40 be provided with the present arrangement of grooves or openings by cutting the same therein, and therefore I do not wish to be understood as limiting the application of the invention to artificial blocks alone.

Having thus described the invention, what 45 is claimed, and desired to be secured by Letters Patent, is—

1. A building-block wherein there are no continuously solid portions from front to rear. 50
2. A building-block having a plurality of longitudinal openings, some of which intersect the top and bottom of the block respectively, and adjacent openings being overlapped so as to prevent continuous solid portions from front to rear of the block at any point therein. 55
3. A building-block having a pair of longitudinal grooves or openings which extend beyond the middle of the block and thereby 60 overlap one another, one of the grooves or openings intersecting the top of the block and terminating short of the bottom, and the other intersecting the bottom and terminating short of the top of the block. 65
4. A building-block having a pair of longitudinal grooves or openings which extend beyond the middle of the block and thereby 70 overlap one another, one of the grooves or openings intersecting the top of the block and terminating short of the bottom, the other intersecting the bottom and terminating short of the top of the block, and both grooves or openings intersecting the same end of the block. 75
5. A building-block having a pair of longitudinal grooves or openings which extend beyond the middle of the block and thereby 80 overlap one another, one of the grooves or openings intersecting the top of the block and terminating short of the bottom, the other intersecting the bottom and terminating short of the top of the block, and both grooves or openings intersecting each end of the block.

FRANK W. BLAKESLEE.

In presence of—

CLARA A. GAPE,
GLADYS E. CORNWELL.
